UNITED STATES PATENT OFFICE.

MOÏS H. AVRAM, OF NEW YORK, N. Y., ASSIGNOR TO SLOCUM, AVRAM & SLOCUM, INC.,
OF NEW YORK, N. Y., A CORPORATION OF NEW YORK.

AUTOMATIC TIME-SWITCH.

1,279,964.

Specification of Letters Patent. Patented Sept. 24, 1918.

Application filed May 24, 1915. Serial No. 29,981.

To all whom it may concern:

Be it known that I, Moïs H. AVRAM, a citizen of the United States, and a resident of New York city, county, and State of New York, have invented certain new and useful Improvements in Automatic Time-Switches, of which the following is a specification.

This invention relates to an automatic time switch of novel construction which is more particularly designed to be used in conjunction with an efficiency recorder for machines, etc., such as for instance shown and described in United States Patent No. 1,181,104 granted to me March 9th, 1915. I have found it to be of the utmost importance with respect to a reliable operation of such a recorder that the electric contact which is intermittently closed by the machine to be controlled, be maintained for a certain length of time as in this way only, a proper energizing of the electromagnets that form part of the efficiency recorder, may be relied upon. The invention further comprises other novel features of construction more fully brought out in the appended specification and claims.

In the accompanying drawing,

Figure 1 is a face view of my improved time switch and coöperating parts;

Fig. 2 a side view of Fig. 1;

Fig. 3 an enlarged view partly in section of the time switch with the cover removed;

Fig. 4 a cross section on line 4—4, Fig. 3;

Fig. 5 a similar section on line 5—5, Fig. 3, and

Fig. 6 a detail of the feed pawl-controlling cam.

The casing of my improved time switch comprises a base plate 10 and a cover 11 dust-tightly secured to said plate by means of screws 12. Into a perforation of a depressed portion 13 of plate 10 is firmly driven a bolt 14 upon which is free to rotate a sleeve 15 the lower flange 16 of which is accommodated within a corresponding recess 17 of base plate 10. Sleeve 15 is held to bolt 14 by means of an adjustable feed pawl-controlling cam plate 18 hereinafter more fully referred to, said cam being secured to plate 10 by means of a screw 19 and engaging flange 16. Sleeve 15 is accommodated within a corresponding bore 20 of cover 11 and passes through a dust-proof stuffing box 21. Upon the protruding angular portion 22 of sleeve 15 is fitted the hub

23 of a lever 24 provided with a longitudinal slot 25. To lever 24 is adjustably clamped a block 26 into a perforation of which is oscillatably fitted a bolt 27. The head 28 of the latter is provided with a transverse bore 60 adapted for the reception of a bipartite reciprocal rod 29 which is, by clamp 30, connected to a suitable oscillative part of the machine to be controlled. In order to prevent a breakage of the parts described in 65 case they are not properly adjusted, a yielding connection is provided between the clamp 30 and lever 24, which is shown to consist of a pair of springs 31 interposed between the head 28 and abutments 32 of 70 rod 29.

The flange 16 of sleeve 15 is provided with a radially extending arm 33 to which is pivoted a pawl 34 influenced by a spring 35 that is attached to said arm. Spring 35 holds 75 the pawl 34 in engagement with a ratchet wheel 36 loosely mounted on sleeve 15, a spring-influenced detent 37 preventing an undesired backward rotation of the ratchet wheel 36. To the latter is keyed or otherwise secured a cam wheel 38 shown to be provided with a pair of diametrically opposed teeth 39 although it is obvious that it may be provided with a different number of such teeth as conditions may require. 80

Each of the teeth 39 is adapted to engage the laterally protruding arm or nose 40 of a plunger 41 having a stem 42 that is slidably supported by a suitable bearing 43 of base plate 10. Plunger 41 is furthermore 90 provided with a head or piston 44 that slidably engages a cylinder 45 secured to the base plate 10. Intermediate plunger 41 and bearing 43 there is provided a spring 46 encircling stem 42 and tending to force the 95 piston 44 into cylinder 45. During the oscillation of the lever 24 the ratchet wheel 36 is intermittently advanced thereby advancing the teeth 39 of cam wheel 38 in the direction of the arrow (Fig. 3). In this 100 way, the tooth 39 engaging nose 40 will gradually retract the plunger 41 and piston 44 against the action of spring 46, until the parts have arrived in the position illustrated in Fig. 3, the tooth 39 being about to clear 105 nose 40. As soon as the tooth 39 has released the nose 40, the spring 46 will advance the plunger 41 toward its initial position which advance movement is however retarded owing to the resistance offered by 110

the air entrapped within cylinder 45. As a slight clearance is provided between the piston 44 and the surrounding cylinder 45, the entrapped air will gradually escape, so 5 that the desired comparatively slow advance movement of plunger 41 is obtained.

The retarded movement of the plunger 41 thus produced is utilized for the desired protracted closure of an electric contact 10 which is shown to consist of a pair of contact springs 47, 48 attached to opposite sides of a block 49 of insulating material, which block is in turn secured to base plate 10. Contact spring 47 is adapted to be engaged 15 by one arm 50 of a bell crank lever 51 pivoted at 52 to plunger 41. The other arm 53 of this lever is influenced by a spring 54, the play of arm 53 being limited by a stop 55 provided on plunger 41. It will be seen 20 that during the advance movement of this plunger which takes place upon the disengagement between one of the teeth 39 and nose 40, arm 50 will bend the spring 47 into contact with the spring 48, which contact 25 will be maintained until the lever arm 53 engages a fixed stop 56 of base plate 10. Owing to this engagement, the lever 51 will be tilted during the continued advance of plunger 41 so that the arm 50 will slip off 30 spring 47 and thereby permit the springs 47, 48 to become separated thus again occupying the position illustrated in Fig. 3. As the advance movement of plunger 41 is 35 considerably retarded owing to the provision of piston 44 and cylinder 45 it is obvious that the contact established between the springs 47, 48 will be maintained for the desired length of time for reliably closing the circuit (not shown) controlled by said 40 contact springs. During the subsequent return movement of plunger 41, the lever arm 50 will glide by spring 47, a taking along of said spring being prevented by a fixed stop 57. 45 It will be seen that by properly setting block 26 the angular play imparted to lever 24 may be regulated, said angular play in turn determining the angular play of pawl 34 and consequently the number of teeth of 50 ratchet wheel 36 to be engaged during each oscillation of said pawl. To still further control the intermittent advance movement of ratchet wheel 36, the hereinabove mentioned plate 18 is provided with a cam portion 58 adapted to be engaged by pawl 34. It will be seen that as soon as this pawl engages the cam 58, it will be lifted out of engagement with ratchet wheel 36. By loosening the screw 19 that passes through a segmental slot 59 of plate 18, the cam 58 may be advanced toward or retracted from the pawl 34 thereby either increasing or diminishing the number of ratchet teeth adapted to be engaged by said pawl. 60

65 I have shown but do not herein claim

mechanism to count or record the number of operations of ratchet wheel 36, comprising a toothed wheel 60 firmly attached to the ratchet wheel 36, the number of teeth of said wheel corresponding to the number of 70 teeth on the ratchet wheel. The toothed wheel 60 is engaged by a pinion 61 having ten teeth and secured to the spindle 62 of a counter 63 of convenient construction, the uppermost numbers of said counter being 75 exposed through a window 64 provided in cover 11. The squared end 65 of spindle 62 passes outwardly through a suitable dust-tight stuffing box 66, so that it may be engaged by a key for setting the counter to 80 zero.

Spindle 62 is further provided with a worm 67 engaging a worm wheel 68, that is shown to be furnished with a plurality of 85 sockets 69. The latter are designed for the reception of one or more contact pins 70 adapted to engage a stationary contact 71. By each engagement between a contact pin 70 and the stationary contact 71, a signaling 90 circuit (not shown) is closed by means of which the completion of a suitable number of operations, etc., of the machine to be controlled, may be perceptively announced.

It will be seen that by my novel automatic time switch the electromagnets of the 95 efficiency recorder with which said switch co-operates, may be reliably actuated.

I claim:—

1. In a device of the character described, an oscillatable member adapted to be actuated by the machine to be controlled, a spring-influenced plunger, means whereby said plunger is adapted to be operated intermittently by said member in opposition to its spring, a pair of contacts adapted to be closed by and during the advance movement of the plunger under the influence of its spring, means for retarding said advance movement of the plunger and means controlled by said plunger but independently 100 actuated for breaking said contact near the end of the advance movement thereof. 110

2. In a device of the character described, an oscillatable member adapted to be actuated by the machine to be controlled, a spring-influenced plunger, means whereby said plunger is adapted to be operated intermittently by said member in opposition to its spring, a piston carried by the plunger, a stationary cylinder adapted to be engaged by said piston, said piston and cylinder jointly constituting means for retarding the advance movement of the plunger under the influence of its spring, and a contact making and breaking device 120 controlled by said plunger for closing the contact during said advance movement, said last named device being independently actuated for breaking said contact near the end 125 of the advance movement of said plunger. 130

3. In a device of the character described, an oscillatable member adapted to be actuated by the machine to be controlled, a spring-influenced plunger, means whereby said plunger is adapted to be operated intermittently by said member in opposition to its spring, a spring-influenced lever fulcrumed to said plunger, a pair of contacts adapted to be closed by said lever during the advance movement of the plunger under the influence of its spring, means for retarding said advance movement of the plunger and means for rocking said lever near the end of the advance movement of said plunger for breaking said contacts. 50
4. In a device of the character described, an oscillatable member adapted to be actuated by the machine to be controlled, a spring-influenced plunger, means whereby said plunger is adapted to be operated intermittently by said member in opposition to its spring, a spring-influenced lever fulcrumed to said plunger, a pair of contacts adapted to be closed during the advance movement of the plunger under the influence of its spring, means for retarding said advance movement of the plunger, means carried by said plunger for positively closing said contacts and independent means coöperating therewith for breaking said contacts near the end of the advance movement of said plunger. 60
5. In the device of the character described, an oscillatable member adapted to be actuated by the machine to be controlled, a spring-influenced plunger, means whereby said plunger is adapted to be operated intermittently by said member in opposition to its spring, and means for retarding said advance movement of the plunger, said lever being automatically rocked to open said contacts near the end of the advance movement of said plunger. 65
6. In a device of the character described, an oscillatable member adapted to be actuated by the machine to be controlled, a ratchet wheel adapted to be intermittently advanced by said member, a cam secured to said ratchet wheel, a spring-influenced plunger adapted to be actuated by said cam in opposition to its spring, a pair of contacts adapted to be closed during the advance movement of the plunger under the influence of its spring, means for retarding said advance movement of the plunger, means carried by said plunger for positively closing said contacts and independent means coöperating therewith for breaking said contacts near the end of the advance movement of said plunger. 70
7. In a device of the character described, an oscillatable member adapted to be actuated by the machine to be controlled, a pawl adapted to be actuated by said member, a ratchet wheel adapted to be actuated by said member, a ratchet wheel adapted to be actuated by said pawl, adjustable means for varying the number of teeth of the ratchet wheel to be engaged by the pawl, a cam secured to said ratchet wheel, a spring-influenced plunger adapted to be actuated by said cam, in opposition to its spring, a pair of contacts adapted to be closed during the advance movement of the plunger under the influence of its spring, means for retarding said advance movement of the plunger, means carried by said plunger for positively closing said contacts and independent means coöperating therewith for breaking said contacts near the end of the advance movement of said plunger. 75
- 40 to be engaged by the first arm of said bell crank lever, a spring for normally holding said first arm in engagement with said stop, an additional fixed stop adapted to be engaged by said first arm, and a pair of contacts adapted to be closed by the second arm 80
- 45
